ARTIFICIAL TEETH

Hermann Schröder, Charlottenburg-Westend, and
Robert Nussbaum, Lankwitz, GermanyApplication August 8, 1931, Serial No. 555,912
In Germany November 6, 1930

1 Claim. (Cl. 32—8)

It has already been suggested to form artificial teeth in such a manner, that the masticating surface of the one tooth angular at the edge is hollowed out in order to form a mould, whilst the masticating surface of the opposite tooth is made to possess a cupola or dome-shaped form of a lesser radius of curvature.

This arrangement embodies, however, the disadvantage, that the given centering of the teeth to each other renders a certain placement of same in the position of occlusion necessary.

It has further been suggested to provide cavities in the molar teeth of the inferior maxilla, being formed by three faces intersecting at an angle of 110°, the edges of which meet under an angle of 120° and that in such a manner, that the tectiform or roof-shaped masticating surfaces of the superior maxilla, being provided with a bevel of a certain angle in the direction of the cheek, match the cavity. The cavity, being formed by a certain trihedral angle arrangement, is situated in every single tooth. This configuration does not, however, render a free and unhindered maxillary movement possible during the masticating process, because the molars of the inferior maxilla have been provided with ascending bevels in the direction of the cheeks and in consequence thereof the teeth of the superior maxilla are forced to glide up with the tectiform or roof-shaped part of the masticating surfaces of the upper molars along said bevels during the lateral and mixed lateral and forward motion of the teeth. In view of the fact, that thereby certain points of the teeth of the inferior and superior maxilla establish contact with each other, which originally have not been intended to do so, there will be a possibility of easily lifting off the prosthesis carrying the artificial teeth. The same applies to another kind of arrangement which has become known, in which the masticating surfaces of the teeth are provided with small protuberances or projections.

One of the objects of the present invention is to provide artificial teeth which will facilitate as much as possible the mixed lateral and forward motions controlled by the motion of the maxillary joint during the masticating process.

There will also be a possibility to impart to the teeth an appearance fully corresponding to the cosmetic assumptions when producing a prosthesis. By the arrangement of the upper faces of the teeth it has been rendered possible, when constructing a prosthesis, to displace the longitudinal axis or a part of the longitudinal axis of the one or the other row of teeth in the direction

of the cheeks as well as towards the tongue, so that the teeth may be accommodated to various kinds of mastication.

The above-mentioned object of the present invention may be realized by providing a curved transverse ledge on the dome-shaped teeth and/or the counter teeth, which form the prosthesis.

The dome-shaped molar teeth and/or the counter teeth may be provided with a substantially S-shaped transverse ledge allowing lateral and longitudinal movements as well as every kind of combined lateral and longitudinal movements of the teeth.

The S-shaped configuration of the transverse ledge is particularly advantageous for that reason that, on the one hand, it improves the chewing process and, on the other hand, it allows the transverse ledge to glide outwards without being interfered with, owing to the fact that the mould or recess, being formed by two adjoining teeth, shows no projection or protuberance which has to be passed, as a result of the situation of the S-shaped transverse ledge at the mesial sides of the molars towards the cheeks and at the distal sides of the molars towards the tongue, so that a practically unimpeded lateral motion and a mixed lateral and forward motion to the fullest possible extent of all maxillary motions that may be possible, is ensured.

The masticating surfaces of the frontal premolars show in accordance with the present invention in the forward section a short, horizontal surface, or a surface which is slightly inclined upwards or downwards, whilst they are forming the mould or recess in the rearward section. The tooth has, therefore, been given a dissymmetric shape and that for the reason of its functional purposes.

The highest part of the cupola or dome-shaped teeth and of the mould or recess teeth may be placed in the centre of the teeth or in front or behind the centre of the teeth for the purpose of attaining articulatory correct proportions in accordance with the prevailing requirements.

The upper surfaces of the teeth may be smooth or they may show channelled indentations.

In the accompanying drawing the invention has been illustrated by way of example,

Fig. 1 being a side view of the premolars and molars of the right half of a set of teeth, whilst

Fig. 2 is a plan view of the teeth of the inferior maxilla in accordance with Fig. 1.

Fig. 3 is a sectional view on the line A—B of Fig. 2, and

Figs. 4 and 6 are further examples of per-

formance of the teeth forming the moulds or recesses, and

Fig. 5 represents a sectional view on line C—D in accordance with Fig. 4.

5 Fig. 7 shows teeth having transverse ledges of a different shape.

In the example of performance in accordance with Figs. 1-3 the teeth of the superior maxilla, *a*, *b*, *c*, *d* are dome-shaped and are engaging in the recesses or moulds between each two of the teeth of the inferior maxilla. Each two of the teeth of the inferior maxilla are forming a mould or a recess in which the dome-shaped tooth appertaining thereto, engages. These moulds or recesses

10 may be of the most heterogeneous designs. In the example of performance in accordance with Figs. 1 to 3, the moulds or recesses are made to be concave in longitudinal, as well as in cross section. They may, however, as shown by the example of

15 performance in accordance with Figs. 4 and 5, also be concave in longitudinal section and plane in cross section, in which case the surface of the mould or recess forms a cylindrical surface. As shown in Fig. 6, the surface may also be plane in longitudinal section and, in accordance with Fig. 3, trough-shaped; in this case, too, the surface of the mould is cylindrical. The above is true of a side of one tooth. Furthermore, however, the moulds

20 may be plane not only in longitudinal section, but also in cross section and this would represent a

longitudinal section in accordance with Fig. 6 and a cross section in accordance with Fig. 5.

The lower frontal premolar *e* is of such dissymmetrical design, that it shows in its front section a face *i* being straight or slightly inclined forward and downward and occupying about $\frac{1}{3}$ to $\frac{1}{2}$ of the total surface, from the rearward edge of which a straight or concave surface *k* is extending obliquely rearwardly and downwardly under a rather accentuated angle.

10 As seen from Fig. 1, and particularly from the tooth *c*, the dome-shaped teeth may be provided with a transverse ledge *m* being situated either in front or behind the centre of the tooth.

Fig. 7 shows an S-shaped ledge having its two 15 ends bent in opposite directions, which can be used on dome shaped teeth and/or on counter teeth.

We claim:

In a set of artificial teeth, in combination, a 20 pair of counter teeth forming a recess, a dome-shaped molar tooth of one maxilla adapted to engage in said recess, and a substantially S-shaped transverse ledge on at least one of said teeth, said ledge allowing lateral and longitudinal 25 movements as well as every kind of combined lateral and longitudinal movements of the teeth.
